(57) **CLAIM**

The ornamental design for a carrying case with a magnetic securing flap, as shown and described.

DESCRIPTION

FIG. 1 is a front perspective view of a carrying case with magnetic securing flap, shown with a front closure flap and a rear securing flap in extended open positions;

FIG. 2 is a front elevational view of the carrying case with magnetic securing flap of FIG. 1, shown with the front closure flap in a folded closed position;

FIG. 3 is a rear elevational view of the carrying case with magnetic securing flap of FIG. 1, shown with the rear securing flap in a folded closed position;

FIG. 4 is a right side elevational of the carrying case with magnetic securing flap of FIG. 1, shown with the front closure flap and the rear securing flap in folded closed positions;

FIG. 5 is a left side elevational of the carrying case with magnetic securing flap of FIG. 1, shown with the front closure flap and the rear securing flap in folded closed positions;

FIG. 6 is a front elevational view of the carrying case with magnetic securing flap of FIG. 1, shown with the front closure flap and the rear securing flap in extended open positions; and,

FIG. 7 is a rear elevational view of the carrying case with magnetic securing flap of FIG. 1, shown with the rear securing flap in an extended open position.

The broken lines in the drawings illustrate portions of the carrying case with magnetic securing flap which form no part of the claimed design.

1 Claim, 5 Drawing Sheets
